TOY

Aimee J. Dube, Troy, N. Y.

Application December 13, 1946, Serial No. 716,039

7 Claims. (Cl. 46—130)

1

This invention relates to a novel construction of gravity actuated toy of extremely simple construction and which is capable of being economically manufactured and sold and which will afford great amusement to children.

It is a primary object of the present invention to provide a toy including a gravity propelled, preferably a wheeled vehicle disposed for movement along a rail by gravity and due to the inclination of the rail, which in its travel will engage a stop, carried by the rail for causing a resulting movement of the rail relatively to the supports for the ends thereof and consequent movement of the ends of the rail in said supports for alternately positioning said rail ends at different levels, so that the wheeled vehicle will be caused to be moved back and forth along the rail.

More particularly, it is an object of the invention to provide a toy wherein by lateral displacement of the rail due to the impact of the wheeled vehicle with stops thereof, said rail will be caused to traverse a step by step downward displacement relatively to its end supports and in so moving the rail will be alternately inclined in opposite directions.

Still a further object of the invention is to provide a toy of the aforescribed character and which is capable of being inverted so that the supporting rail may traverse a course in either direction of its end supports which, in either instance, will be in a downward direction.

Various other objects and advantages of the invention will hereinafter become more fully apparent from the following description of the drawings, illustrating the preferred embodiment thereof, and wherein:

Figure 1 is a side elevational view of one embodiment of the invention;

Figure 2 is a horizontal sectional view, on an enlarged scale, taken substantially along a plane as indicated by the line 2—2 of Figure 1;

Figure 3 is a perspective view of one end of the supporting rail or rod of the toy;

Figure 4 is a fragmentary side elevational view of a slightly modified form of the embodiment of the invention as illustrated in Figures 1 to 3;

Figure 5 is a perspective view of a portion of one of the uprights and illustrating a variation of Figure 4;

Figure 6 is a view similar to Figure 5, illustrating another variation of Figure 4;

Figure 7 is a fragmentary perspective view illustrating still another variation of Figure 4;

Figure 8 is a view similar to Figure 3 and illus-

2

trating a modified form of the rod or rail for use with the modifications of Figures 4, 5, 6 and 7;

Figure 9 is a side elevational view of another embodiment of the invention;

5 Figure 10 is a horizontal sectional view thereof taken substantially along a plane as indicated by the line 10—10 of Figure 9;

Figure 11 is a transverse vertical sectional view taken substantially along a plane as indicated by the line 11—11 of Figure 9, and

Figure 12 is a horizontal sectional view taken substantially along a plane as indicated by the line 12—12 of Figure 9.

Referring more specifically to the drawings, in the embodiment of the invention as illustrated in Figures 1 to 3, the toy, designated generally 13, includes a pair of uprights 14 and 15, each of

15 which is channel-shaped in cross section, as seen in Figure 2, and which are secured and spaced apart, in substantially parallel relationship by

20 means of the end members 16. The end members 16 preferably comprised of substantially flat bars which are fastened adjacent their ends in any suitable manner to the ends of the uprights 14

25 and 15 and which are provided with widened, substantially T-shaped end portions 17. The uprights 14 and 15 and the end members 16 combine to form the frame of the toy 13 which is adapted to be disposed in an upright position

30 supported on either of the end members 16 as a base. It will be readily apparent that the laterally projecting end portions 17 will increase the width of the portion 16, functioning as a base, to provide a stable support for the frame when in

35 engagement with a supporting surface such as a table, not shown.

The upright 14 is provided in the complementary sides 18 thereof with corresponding longitudinally extending outwardly bowed upper and lower slots 19 and 20 which are disposed in spaced apart and end to end relationship. The adjacent ends of the complementary slots 19 and 20 of each side 18 are connected by an angular slotted portion 21 each of which includes an upwardly

40 facing upper shoulder 22 having an outwardly facing free end and a downwardly and outwardly offset lower shoulder 23 which also faces upwardly and which opens inwardly. The upper end of each slot 19 opens into a transverse slot 24

45 forming an upwardly facing inwardly opening shoulder 25. The lower end of each slot 20 opens into a slotted portion 26 having an upwardly facing outwardly opening shoulder 27 at its upper end, an upwardly facing inwardly opening shoul-

45 der 28, intermediate of its ends and outwardly

50

55

55

offset with respect to the shoulder 27, and an enlarged, substantially circular lower end 29 provided with a restricted inwardly extending slot 30 opening into the inner edge of its side 18.

The sides 31 of the upright 15 are provided with upper and lower longitudinally extending outwardly bowed slots 32 and 33, respectively, corresponding substantially to the slots 19 and 20 but offset downwardly somewhat with respect thereto, when the uprights 14 and 15 are in the position as seen in Figure 1. The adjacent ends of the complementary slots 32 and 33 are connected by a portion 34 corresponding to the slotted portion 21 and including the upwardly facing shoulders 35 and 36 corresponding to the shoulders 22 and 23, respectively. As seen in Figure 1, the portion 34 is located below the level of the portion 21. The upper end of each slot 32 communicates with an angular slotted portion 37, located below the level of the transverse slotted portion 24 and which includes an upper, upwardly facing and outwardly opening shoulder 38 and a lower, outwardly offset upwardly facing and inwardly opening shoulder 39. The lower end of each slot 33 communicates with a slotted portion 40, corresponding to the slotted portion 26 and including shoulders 41 and 42, corresponding to the shoulders 27 and 28, respectively, and a portion 43 having a passage 44, corresponding to the portion 29 and its passage 30.

The sides 18 and 31, over the slotted portions 24, 26, 37 and 40 are provided with cover plates 45 suitably secured to the outer sides thereof and having portions, overlying said slotted portions, bowed outwardly and away from said sides as clearly illustrated in Figure 2.

A rod 46 forming a rail for a wheeled vehicle 47 is provided with transversely disposed crossheads 48 at the ends thereof adapted to be disposed in the channels of the uprights 14 and 15, as seen in Figure 2, and with the terminal portions of the crossheads engaging slots of the sides of said uprights. In its initial position, the rod 46 is disposed as seen in Figure 1 with the ends of one of the crossheads 48 resting on the shoulders 25 and the ends of the other crosshead 48 resting on the shoulders 38. The rod 46 is also provided adjacent its ends with substantially upright cross members 49 forming stops, between which the wheeled vehicle 47 is movable on said rod 46. The wheeled vehicle 47 will preferably assume the embodiment of a unicycle, as seen in Figure 11, having a grooved wheel for engagement with the rod 46, as seen at 50, which is journaled in the axle of a support 51 one leg of which is extended downwardly and offset inwardly to position a weight 52 directly beneath the plane of the wheel 50. As seen in Figure 1, the upper end of the support 51 is preferably provided with a saddle on which a figure 53 of any desired simulation may be disposed.

The weight 52 maintains the wheeled vehicle 47 in its upright position of Figure 1 and it will be readily apparent that the inclined position of the rod 46 will cause the vehicle 47 to travel from left to right of Figure 1 until the wheel 50 strikes the right hand stop 49. This impact will cause the rod 46 to be displaced from left to right of Figure 1 thereby disengaging the crossheads 48 from the shoulders 25 and 38. The right hand crosshead 48 will drop onto the shoulder 39 and the left hand crosshead 38 will slide down the arcuate slot 19 onto the shoulders 22, as seen in dotted lines in Figure 1. The rod 46 thus posi-

tioned, will be inclined in the opposite direction so that the vehicle 47 will travel backward or from right to left until its wheel 50 strikes the left hand stop 49 thereby displacing the rod 46 toward the left and so that its left hand crosshead 48 will drop onto the shoulders 23 and the right hand crosshead 48 will slide down the slots 32 and onto the shoulders 35. After the vehicle 47 has traversed the rod again from left to right and said rod has been displaced again toward the right, the left hand crosshead 48 will move down the slots 20 onto the shoulders 27 and the right hand crosshead 48 will be in position on the shoulders 36 to repeat the movement of the vehicle and rod in the opposite direction. This will cause the left hand crosshead 48 to drop onto the shoulders 28 and the right hand crosshead to slide down the slots 33 and onto the shoulders 41. The vehicle 47 will then move again from left to right and displace the rod 46 to the right so that the left hand crosshead 48 will drop into the slotted openings 29 and the right hand crosshead will come to rest on the shoulders 42. The rod 46 may then be disengaged from the uprights through the movement of the crosshead 48 outwardly of the passages 30 and 44 or the uprights may be inverted and supported by the other end member 16. The rod 46 is removed only in the event that it is desired to make some adjustment to the toy and the normal operation is to invert the uprights.

After inverting the uprights, one of the crossheads 48 is positioned on the then upwardly facing shoulders 54 of the upright 14 and the other crosshead 48 is positioned on the then upwardly facing shoulders 55 of the upright 15. It will be readily apparent that the wheeled vehicle 47 can then repeat the previously described operation as the ends of the rods 46 move alternately and intermittently toward the opposite ends of the uprights 14 and 15.

A modification of the embodiment of Figures 1 to 3 is illustrated in Figure 4 wherein one of the uprights 15¹ is shown provided with spaced inwardly opening notches 56 in the sides thereof and it will be readily obvious that the other upright, not shown, will be provided with similarly disposed notches, not shown, arranged at slightly higher levels. Associated with each notch 56 is an arm 57 having an upper portion secured to the outer side of the upright 15¹, above the adjacent notch 56 and extending inwardly and being offset outwardly therefrom. Each arm 57 terminates in a downwardly extending portion 58, spaced inwardly from its associated notch 56 and provided with an inwardly extending supporting arm 59. A bracket 57, 58 and 59 is associated with each of the upper notches 56. The intermediate notches 56 of the uprights 15¹ are each provided with a bracket including an outwardly bowed arm 60 fastened to the upright 15¹ and having a longitudinal portion 61 spaced from its associated notch 56 and provided with an inwardly extending intermediate arm 62. The lower notches 56 of the upright 15¹ each have a bracket associated therewith including a supporting arm 63 which is bowed outwardly and secured at one end to the upright 15¹ and which is provided with a transversely disposed opposite end 64 the lower end of which terminates in the inwardly extending portion 65.

The rod 46¹ differs from the rod 46 in that it is provided with an extension at each end thereof beyond each of its crossheads 48¹, said extensions being designated 66 and extending into the chan-

nels of the uprights. With the upright 15¹ in its position of Figure 4 one of the crossheads 48¹ is initially positioned on the bracket arm 59 and is displaced to the right therefrom by the wheeled vehicle striking the right hand stop 49¹. Said crossarm 48¹ is thereby displaced downwardly into the notches 56 to rest on the lower edges thereof. When the rod 46¹ is next displaced to the left, said right hand crossarm 48¹ will slide down the inner concave edges 61 onto the arms 62 and will thereafter slide down the edges 68 onto the arms 65. The other upright, not shown, will correspond to the upright 15¹ as it would appear in an inverted position, so that a description of the movement of the aforementioned end of the rod 46¹ in the opposite direction on the inverted upright 15¹ will describe the movement of the opposite end of the rod 46¹ in the initial movements of the rod 46¹, as previously described. Assuming that the upright 15¹ is inverted, the crossarm 48¹ will rest on the shoulder 69 and when displaced to the right will slide down the edges 68 onto the supporting arm 62. When next displaced to the left, said crossarm 48¹ will drop into the notches 56 and come to rest on the then bottom edges thereof and when again displaced to the right will slide down the edges 67 and onto the supporting arms 59.

The brackets 70', as illustrated in Figure 5, may be substituted for the brackets 57, 58, 59 and differ therefrom only in that the arms 57¹ thereof are inclined downwardly away from their secured ends. The brackets 71' of Figure 6 differ from the brackets 60, 61 and 62 in that the brackets 71' are formed of substantially flat metal stock whereas the aforescribed brackets are of metal of substantially circular cross section. The brackets 72' of Figure 7 may be substituted for the brackets 63, 64 and 65 and likewise are formed of flat instead of circular stock and differ therefrom in that the brackets 72' include upright portions 73', corresponding to the portions 64 and having a supporting arm 74', one end of which performs the function of the arm 65, the other end of which is secured to the upright 15¹. The intermediate portion of the arm 74' is bent outwardly with respect to the adjacent side of the upright 15¹.

Another form of the invention is shown in Figures 9 to 12 and includes a base 70 forming a support for two spaced uprights 71 and 72. The base 70 is provided with T-shaped ends forming lateral extensions 73 corresponding to the extensions 17 of the bases 16. The uprights 71 and 72 are each formed from a substantially flat bar which are connected adjacent their upper ends by a crossbar 74, forming a brace, which is laterally offset relatively to the uprights 71 and 72, as seen in Figure 10 and so as not to interfere with the movement of the wheeled vehicle 47. The upright 71 is taller than the upright 72 and is provided with a longitudinal slot, designated generally 75, which is substantially identical to either of the slotted sides of the upright 14 except that the circular lower portion thereof is not provided with an inwardly opening passage similar to the passage 30. The upright 72 is provided with a slotted portion, designated generally 76, corresponding substantially to the slotted portion of either of the sides of the upright 15 except that its circular lower portion is likewise not provided with a passage, such as the passage 44. The toy as illustrated in Figures 9 to 12 also includes a rod 77 forming a rail for the wheeled toy 47, which corresponds with the wheeled toy

of Figure 1. The rod 77 is provided with stops 78, similarly disposed and for the same purpose as the stops 49 and therebeyond is provided with laterally offset portions 79 which are adapted to be disposed along complementary sides of the uprights 71 and 72 and which terminate in inturned portions 80, as seen in Figure 12, for engagement with the slotted portions 75 and 76. The portions 80 likewise terminate in enlarged heads 81 which engage the opposite sides of the uprights 71 and 72 to the sides thereof, adjacent to which the portions 79 are disposed, and by means of which the rod 77 is retained detachably connected to the uprights 71 and 72. The heads 81 are passable through the openings 82 forming the enlarged lower ends of the slotted portions 75 and 76.

With the rod 77 applied and disposed at the upper ends of the slotted portions 75 and 76, one of the rod portions 80 rests on the upwardly facing shoulder 83 of portion 75 and the other rod portion 80 rests on the upwardly facing shoulder 84 of portion 76. The lateral displacement and also the sliding movement of the ends of the rod 77 will be readily obvious from the previous description of the operation of the toy 13 and therefore to repeat the description is considered unnecessary. The rod 77, after the end portions 80 thereof are in engagement with the slotted portions 82, may either be detached from the uprights or moved back upwardly through the slotted portions 75 and 76 to position the rod 77 in its position of Figure 9 and so that the gravitational propulsion of the wheeled vehicle 47 can then be repeated.

Various modifications and changes are contemplated and may obviously be resorted to, without departing from the spirit and scope of the invention as hereinafter defined by the appended claims.

I claim:

1. In a toy of the character described, a base, a pair of uprights secured thereto and rising therefrom in substantially parallel relationship, said uprights having longitudinally disposed slotted portions including arcuate longitudinal sections and upwardly facing shoulders, a rod having transverse portions for slidably engaging said slotted portions of the uprights and constructed and arranged to rest on said upwardly facing shoulders and to slide relatively to said arcuate portions in response to intermittent oscillatory movement of opposite ends of said rod, a wheeled vehicle adapted to be propelled by gravity from adjacent one end to adjacent the opposite end of said rod, and said rod having stops forming abutments for the wheeled vehicle by the impact of which said rod is laterally displaced relatively to the uprights and thereby caused to oscillate and slide relatively to the slotted portions of said uprights for positioning the opposite ends of the rod alternately in elevated position whereby said vehicle will be caused to move alternately from end to end of the rod.

2. A toy as in claim 1, said uprights being channel shaped and having complementary parallel sides provided with complementary slotted portions, and said rod having crossarms at its ends for engagement with the complementary slotted portions.

3. A toy as in claim 1, said uprights each being formed of a substantially flat bar, said rod having complementary inturned end portions extending through the slotted portions of the uprights, and said inturned rod portions having heads of a

width greater than the width of said slotted portions.

4. In a toy of the character described, a pair of spaced uprights having a plurality of upwardly facing shoulders, a rod disposed between said uprights and having portions for engagement with said shoulders, a gravitationally propelled vehicle mounted for movement in either direction along said rod, and said rod being provided with stop portions adjacent its ends forming abutments for said vehicle, said rod being adapted to be initially disposed at an incline whereby said vehicle will be gravitationally propelled toward the lower end thereof and into engagement with the stop, disposed adjacent said end, for laterally displacing said rod in response to the impact of the engagement of the vehicle with said stop, and said shoulders being constructed and arranged whereby when the rod is thus displaced the lower end thereof will drop onto another upwardly facing shoulder and the upper end thereof will swing downwardly on said last mentioned shoulder as a pivot and into a position below the level of the previously disposed, lower end of the rod, so that said vehicle will be gravitationally propelled toward the stop at the opposite end of the rod causing a repetition of the displacement of the

rod and the dropping and swinging movement thereof.

5. A toy as in claim 4, certain of said upwardly facing shoulders being formed integral with the uprights, and brackets supported by the uprights and having portions forming other of the upwardly facing shoulders.

10 6. A toy as in claim 4, and crossheads connected to the complementary ends of said uprights, each of said crossheads forming a base for supporting the uprights and whereby the uprights may be inverted to permit movement of the rod downwardly in response to the action of the gravitationally propelled vehicle in either direction with respect to the uprights.

15 7. A toy as in claim 4, said gravitationally propelled vehicle including a fork, a wheel journaled therein and adapted to engage said rod, and an arm depending from one side of said fork and having an offset lower portion provided with a weight disposed with its axis in alignment with the plane of the wheel for maintaining the vehicle in an upright position on said rod.
